(57) **CLAIM**

The ornamental design for “expandable swaddling garment”, as shown and described.

DESCRIPTION

FIG. 1 illustrates a front elevational view of a the expandable swaddling garment, in a contracted configuration, showing my new design;

FIG. 2 illustrates a rear elevational view thereof;

FIG. 3 illustrates a right side elevational view thereof;

FIG. 4 illustrates a left side elevational view thereof;

FIG. 5 illustrates a top plan view thereof;

FIG. 6 illustrates a bottom plan view thereof;

FIG. 7 illustrates a front elevational view of the expandable swaddling garment illustrated by FIG. 1, in an expanded configuration;

FIG. 8 illustrates a rear elevational view of the expandable swaddling garment illustrated by FIG. 7;

FIG. 9 illustrates a right side elevational view of the expandable swaddling garment FIG. 7;

FIG. 10 illustrates a left side elevational view of the expandable swaddling garment illustrated by FIG. 7;

FIG. 11 illustrates a top plan view of the expandable swaddling garment illustrated by FIG. 7; and,

FIG. 12 illustrates a bottom plan view of the expandable swaddling garment illustrated by FIG. 7.

The broken lines shown illustrate stitching on the expandable swaddling garment that forms a part of the claimed design.

1 Claim, 9 Drawing Sheets
